UNITED STATES PATENT OFFICE

2,578,386

GUN SIGHT MOUNTING

Harvey A. Williams, Davison, Mich.

Application March 12, 1949, Serial No. 81,033

1 Claim. (CL 33—56)

1 This invention relates to gun sight mountings generally and more particularly to a novel elevation and windage setting adjustment for the sight which is incorporated into the mounting. The application is a continuation in part of the inventor's copending application No. 20,051, filed April 9, 1948, entitled Gun Sight Mounting which is now held abandoned.

Heretofore, receiver sight mountings have been provided with elevation and windage adjustments which for their setting depended upon relatively large knurled knobs extending outwardly from the mounting, itself. These knobs are not only unsightly and cumbersome, but are subject to either accidental displacement from a fixed setting or undesirable displacement by unauthorized tampering therewith on the part of unauthorized parties. By means of the novel provision of the present invention, the foregoing disadvantages have been eliminated and a more desirable gun sight mounting has been provided in which substantially permanent elevation and windage adjustments may be made and maintained.

An object of the present invention, therefore, is to provide a novel gun sight mounting.

Another object of the invention is to provide in a receiver sight mounting novel elevation and windage adjustment features by means of which external knobs, heretofore required, have been eliminated.

A further object is to provide a novel mounting for a receiver sight in which the adjustment members for the different necessary settings, such as elevation and windage settings, are in a plane flush with or slightly below the outer portion of the mounting so that accidental displacement of the settings is prevented.

Another object is to provide in a receiver sight mounting, a novel locking expedient embodying a "click" for maintaining a desired adjustment for either elevation or windage settings or both.

A still further object is to provide a novel receiver sight mounting in which the transverse portion of the mounting supporting the sighting member is supported at both of its ends on the receiver.

Another object is to provide a novel receiver sight mounting in which the outer ends of the arm which embody the windage and elevation adjustment screws are of greater thickness than the central portion of the arm so that a mounting is thereby provided which possesses fewer parts and is considerably stronger and less expensive to construct than prior mountings.

2 Other objects and advantages of the invention will become apparent from the following specification, the accompanying drawings, and the appended claim.

5 In the drawings, wherein like reference characters refer to like parts throughout the several views:

Fig. 1 is a side elevation of a form of the invention.

10 Fig. 2 is a plan view of the form of Fig. 1.

Fig. 3 is a vertical section taken on line 3—3 of Fig. 1.

Fig. 4 is a cross section taken on line 4—4 of Fig. 3; and

15 Fig. 5 is a cross section taken on line 5—5 of Fig. 4.

As shown in Figs. 1—5 the mounting block 101, which is suitably secured to the side of the receiver (shown in dotted lines), has a lengthwise dovetail slot 103 opening into its outer face 105. A leg 107 of the L-shaped bracket member 109 is fitted to and slidable in the slot 103 so that the bracket is restrained against all but vertical or elevational adjustment. The leg 107 is held in

25 fixed vertical position by means of a movable wedge block 111 that is transversely slidable in an aperture 113 in the block 101 which opens into the slot 103. The wedge 111, which is preferably of general cylindrical form, has an inclined face which engages at 115 with the inclined edge of the leg 107. A screw 117 extends through the block 111 and threads into the mounting block 101 and provides means whereby the wedge block 111 may be tightly forced against the leg 107 to rigidly interconnect the bracket 109 and the mounting block 101.

The bracket member 109 is adjusted in elevation by means of the screw 119, this being done of course when the screw 117, and thus the wedge 40 111, has been loosened. The screw 119 extends through a suitable aperture 121 that is formed in the other leg 123 of the bracket 109 and threads into the mounting block 101. The stub end 125 of the screw 119 is totally housed within the aperture 121 and may have slots 127 whereby it receives torque.

The gun sight 129 is carried by the leg 123 and is movable lengthwise thereof in order to provide windage adjustment. Thus, it slides on the surface of the leg 123 but has a portion 131 which extends downwardly into a lengthwise slot 133 that is formed in the leg 123. An adjusting screw 135 threadably extends through the sight portion 131 and is journaled at each end in apertures 55 137 and 139 that open into the inner ends and

the outer or free end of the slot 133, respectively. The stub end 141 of the screw 135 is totally housed within the bore 139 and may have slots 143 whereby it receives torque.

The stub ends 125 and 141 of the adjusting screws 119 and 135 are adapted to provide the usual "click" and also to serve as means whereby axial movement of the screws is prevented. For this purpose the periphery of each stub end, which may be enlarged as shown, in which case the ends of the leg 123 are also enlarged, has an annular groove 145 and a plurality of angularly spaced detent recesses 147 in the plane of the groove 145. A pin 149 is provided for each groove and these may be formed on the ends of set screws 151 which thread into the edges of the leg 123. The pins 149 serve to prevent axial movement of the adjusting screws without interfering with rotation thereof but by tightening of the screws 151 may be forced against the groove to prevent rotation. Spring pressed detents 153 for the recesses 147 provide the click and, to facilitate manufacture, these are preferably housed in apertures 155 that are diametrically opposite the pins 149.

While bracket 109 is rigidly supported by block 101, leg 123 thereof, may extend unsupported over the receiver. For this reason, the free end of leg 123 is provided with a threaded bore and a screw 157 therein, as shown in Figure 3, which may be adjusted to engage the receiver and thereby provide leg 123 with two points of support.

It will now be apparent to those skilled in the art, that after the gun sight 129 has itself been properly adjusted the windage and elevation settings may be readily performed. For achieving the proper adjustment of the sight in elevation, the wedge 111 is first loosened and then the screw 119 is rotated by means of a suitable tool to raise or lower bracket 109 relative to block 101 and the receiver. On turning of screw 119, detent 153, when engaged by a high point of stub end 125 is cammed or retracted into its cavity against the action of its spring and as soon as the high point or outer periphery of head 125 passes the detent, the latter is pressed by its spring to engage with the next succeeding recess 147. If the desired setting has been attained, the detent by engagement with its recess will hold the screw 119 against displacement. During this adjustment the pin 149 by engagement with groove 145 prevents axial movement of the screw 119 relative to the leg 123. The windage can be adjusted in a similar manner by rotation of screw 135.

It will be observed that the mounting is formed of a minimum number of parts which require relatively few machining operations. The bracket or main support is formed of a single L-shaped bracket rather than several separate pieces, as is often the case. The horizontal arm 123 of the bracket is of substantial thickness and is of greater thickness at each end with the result that it can entirely house the heads of the adjusting screws and is of substantial strength and improved appearance. As a further measure to increase strength and rigidity, the support screw 157 and the dovetail connection 105 with

the wedge block 111 are provided. The bores for set screw 151 and detent 153 are aligned with the result that they can be drilled at the same time and the set screw bore subsequently tapped to form the thread, thus reducing machining operations. Other advantages and features will be apparent to those familiar with gun sights.

It will be evident that various detailed changes may be made in the specific device illustrated without departing from the spirit or scope of the invention.

What is claimed is:

In a gun sight mounting, the combination of a supporting bracket, a block member to be mounted on the gun, a peep sight member, each of said members being connected to said bracket for sliding movement relative to the bracket in directions at right angles to each other respectively, separate means for adjustably fixing each member relative to the bracket, at least one of said means including an adjusting screw journaled in the bracket and threaded into one of said members, said screw having an enlarged head and said bracket having a countersunk screw receiving opening with the screw head positioned within the enlarged portion of the opening, said screw head being provided with click recesses spaced circumferentially about the axis of the screw, said screw head being provided with a circumferential retaining groove intersecting the click recesses and lying in the same transverse plane, said bracket having a blind hole intersecting the screw axis and with portions extending radially on opposite sides of said countersunk opening and located in the transverse plane of said groove, both said hole portions opening into said opening and one terminating at its outer end within said bracket and the other opening at its outer end at a face of the bracket, a spring pressed click detent mechanism in said one hole portion confined between the bottom of said hole and the bottoms of said click recesses, and a retaining set screw threaded into the other hole portion and having one end fitting in said groove and the other end accessible from the face of said bracket into which said hole portion opens.

Certificate of Correction

Patent No. 2,578,386

December 11, 1951

HARVEY A. WILLIAMS

It is hereby certified that error appears in the printed specification of the above numbered patent requiring correction as follows:

Column 4, line 58, list of references cited, for "995,726" read 997,726; and that the said Letters Patent should be read as corrected above, so that the same may conform to the record of the case in the Patent Office.

Signed and sealed this 1st day of April, A. D. 1952.

[SEAL]

THOMAS F. MURPHY,
Assistant Commissioner of Patents.
